UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

AUTOMATIC BOX-BODY AND COVER ASSEMBLING APPARATUS.

Application filed January 6, 1923. Serial No. 610,960.

My invention relates generally to apparatus for automatically assembling sheet metal box bodies and covers, the particular adaptation herein shown and described being 5 for the purpose of assembling boxes of the type commonly used for the packaging of aspirin.

A principal object of the invention is the provision of an assembling apparatus of the 10 character stated, which operates with a full automatic action to advance the box bodies and covers and perform successive assembling operations thereon at a high rate of speed and efficiency and without necessitating particular attention of the attendant.

A further object of the invention is the provision, in apparatus of this character, of devices for automatically preventing congestion of either box bodies or covers in 15 the passageways through which they are fed to and past the assembling mechanism.

A still further object of my invention is the provision of mechanism for preventing the feeding, either of bodies or covers, 20 to the assembly station in the absence of a companion part for assembly therewith.

Other objects and advantages of the invention will be apparent as it is better understood from the following description, 25 which, taken in connection with the accompanying drawing, illustrates a preferred embodiment thereof.

Referring to the drawings,

Figure 1 is a plan view of a machine in 30 which my invention is embodied;

Fig. 2 is a detail perspective of the main drive shaft, showing the driving pulleys and operating cams mounted thereon;

Fig. 3 is an enlarged section taken sub- 40 stantially on the line 3-3 of Fig. 1;

Fig. 4 is a similar section taken substantially on the line 4-4 of Fig. 1;

Fig. 5 is an enlarged transverse section taken substantially on the line 5-5 in 45 Fig. 1;

Fig. 6 is a similar section taken on the line 6-6 of Fig. 1;

Fig. 7 is a detail view, taken substantially on the line 7-7 of Fig. 6 and showing the 50 mechanism for operating the hinge lug bending arm;

Fig. 8 is a sectional detail, looking upwardly, taken substantially on the line 8-8 of Fig. 12 and showing the no-body-no-end device;

Fig. 9 is an enlarged transverse section taken substantially on the line 9-9 of Fig. 1;

Fig. 10 is a similar view taken substantially on the line 10-10 of Fig. 1;

Fig. 11 is an enlarged perspective view of the mechanism for clinching together the hinge forming lugs of the body and cover;

Fig. 12 is an enlarged transverse section taken substantially on the line 12-12 of Fig. 1;

Fig. 13 is a perspective view of the body and cover of an aspirin box adapted to be assembled by an apparatus embodying my invention;

Fig. 14 is a similar view showing the cover and body partially assembled;

Fig. 15 is a perspective view of an assembled box;

Fig. 16 is a cross sectional view through the body and cover prior to the assembly thereof;

Fig. 17 is a similar view showing the cover in its position after the first step of the assembling operation;

Fig. 18 is a like view showing the cover and body in their relationship after being partially assembled and the body brought to horizontal position; and

Fig. 19 is a view of the same parts, showing the finally formed hinge.

Fig. 20 is a detailed section taken substantially along the axis of the body feed control shaft showing the construction thereof.

Attention is first called to Figs. 13 to 19, inclusive, illustrating a box adapted to be assembled by the apparatus of my invention, the sectional views showing the positions and relationship at the various stations in the machine.

The box body 21 may, of course, be of any desired shape, or size, and in the present instance is formed with recesses 22 and a hinge forming lug 23 in the rear wall thereof. The recesses 22 are formed by outwardly extending bead sections and the lug 23 is beaded inwardly so that when brought to final position, a hinge bearing is provided. The box cover 24 has a co-operating hinge forming lug in the rear flange thereof, said flange being cut away so that the ends of said lug project beyond the body thereof, these ends being adapted to be disposed in the recesses 22 when the parts are assembled. The various operations of the machine will be under-

stood by references to Figs. 16 to 19, inclusive, in connection with the description of the mechanism which follows.

The operating parts are supported upon a table 27, which in turn is supported at a suitable elevation from the floor and may be positioned, if desired, in convenient relationship to a press, or other machine performing a preceding operation upon the metal. The box bodies and covers are fed, in any suitable manner as by a conveyer, from such preceding machine into guideways 28 and 29 (Figs. 3, 4 and 5), the former of these being vertically arranged and adapted to have the bodies fed in upright position therethrough and the latter being horizontally arranged, so that the covers may remain in horizontal position throughout their course of travel. These passageways are in adjacent relationship, being arranged respectively along the approximate lines 3—3 and 4—4, as shown in Fig. 1. As a means of directing the bodies and covers along their passageways, I employ compressed air, which is delivered from a supply pipe 31 through branches 32 to a chamber 33, from which openings 34 lead into said passageways.

A safety device is provided for preventing the overcrowding of either the bodies or covers in the channels through which they are fed, this mechanism being illustrated in detail in Figs. 3 and 4. Referring first to Fig. 3, it will be noted that a trap door 35 is provided at the bottom of the channel 28, this door being hinged at 36 and normally held in closed position by means of a spring 37 connected at one end to an arm 38 extending from the pivot of said door, and at the opposite end to a stationary part of the frame.

A slide 39 is mounted in a way 41 which is provided in an upstanding bracket 42, and this slide is constantly reciprocated by means of a link 43, a bell-crank lever 44 and a connecting rod 45 (Fig. 3). The bell-crank 44 is pivoted at 46 to ears 47 upstanding from the table 27, and the rod 45 is reciprocated by certain continuously operating mechanism to be hereinafter described. Upon the slide 39, there is pivotally secured a lever 48 and depending from this lever, at one end, is a rod 49 connected at its lower end with the trap door 35. At the opposite end of said lever 48, a detector rod, or pin, 51 is secured in a slot 52 and extends through a bearing 53 and an aperture 54 into the channel 28. During the constant reciprocation of the slide 39, said pin 51 is permitted to enter the channel 28, if no body be in position to obstruct it, and the door 35 is held in closed position. In the event, however, that the bodies have backed up in the channel 28 so that one is present beneath the aperture 54 upon the downward stroke of the pin 51, the rod 49 is forced downwardly and the trap door 35 opened to permit the

discharge of bodies positioned thereon. Said door 35 is connected by means of a link 55 with a guard wing 56, which is pivoted at 57 to the frame and which obstructs the channel 28 when the door is opened.

Extending from the slide 39 above the lever 48 is a pin 58, which carries at its outer end a lever 59 which serves to operate a detector pin 61, corresponding to the pin 51, and is connected by a rod 62 with a trap door 63 (Fig. 4) at the bottom of the passage 29, being secured thereto by a screw 64. This mechanism operates in a manner similar to that shown in Fig. 3 and further description is, therefore, believed to be unnecessary.

The bodies and covers are directed through the channels 28 and 29, which are illustrated in section in Fig. 5, until the covers arrive beneath an opening 65, as shown in Fig. 1. This opening, of course, permits escape of the air which is employed as a feeding medium and the covers stop until moved further by instrumentalities to be later described. The body channel is cut away at 66 opposite to the opening 65, so that a body and a cover are delivered to stationary positions in alignment substantially on the line 6—6 in Fig. 1.

A can body conveying arm 67 is mounted on a square control shaft 68 (Fig. 20), which is mounted in bearings 69 and 71 (Fig. 1), said arm being movable lengthwise of said shaft through the instrumentality of a slide 72 and an arm 73. Said slide 72 is reciprocated by means of an arm 74, connected therewith by means of a link 70, and carried on a short shaft 75 having bearings 76 on the table 27, said shaft being rotated by an arm 77 (Fig. 5) on a short shaft 78 carrying at its lower end a roller adapted to ride in a groove 79 of an operating cam 81 carried on a main drive shaft 82, these parts being particularly illustrated in Figs. 2 and 5 of the drawings.

A finger 83 is secured to the conveyer arm 67 and is normally disposed in the channel 29 in the path of the box covers, as illustrated in Figs. 5 and 6. The shaft 68 is given intermittent rocking motion by means of an arm 84, a link 85 and a bell-crank lever 86, the latter being mounted on an auxiliary shaft 87 and carrying a cam roller 88 acted upon by a cam 89 on the main drive shaft 82. The upper arm of the bell-crank 86 is connected by means of a spring 80 with a depending flange 80' of the table 27, which tends to hold the conveyer arm 67 in operative position. Rotation of the shaft 68 in counter-clockwise direction lifts the finger 83 and, while in its lifted position, it is moved rearwardly with the arm 67 and when again lowered, it engages within a cover which is moved forwardly upon the next movement of said arm toward the right, viewing Fig. 1.

After the cover has been advanced to the station shown in Fig. 12, it is moved transversely toward the body channel by means of a slide indicated by the reference character 91, said slide being reciprocated by a bell-crank lever 92 connected by a link 93 with a depending arm 94 secured to said slide by means of a screw 95. A cam roller 96 is carried in one arm of the bell-crank 92 and rides 10 in a cam groove 97 in an operating cam 98 carried on the shaft 82.

I shall now describe the mechanism whereby feeding of a body to the assembling station is prevented in the absence of a cover in 15 position to be attached thereto. Upon movement of the slide 91 toward the left, viewing Fig. 12, the cover is brought beneath a retaining plate 99 and above a detector pin 101. Said detector pin normally engages the 20 slide 99 and is rounded at the top to permit of the depression thereof by a cover in passing thereover and at its lower end, rests upon an arm 102 carried upon a shaft 103 having bearings in brackets 104 depending from 25 the table 27. The plate 99 is carried on an arm 105, which is mounted on a shaft 106, the latter being given a slight rocking motion by means of an arm 107, a link 108 and a bell-crank lever 109 mounted on the 30 shaft 87 and carrying a roller 111 riding in the groove of an operating cam 112 upon the shaft 82, these parts being shown most clearly in Fig. 6. If a cover is positioned over the pin 101, the shaft 103 is rotated by the 35 arm 102 and a second arm 113 on said shaft 103 is forced downwardly against the action of a spring 114 secured to said arm and to the bottom of the table 27. Said arm 113 is clearly shown in Fig. 5 in the position assumed 40 when a cover is not present above the pin 101 and it will be manifest that, with the arm 113 in its upper position, a pin on the knuckle 115, forming the connection between the arm 84 and the link 85, is engaged by a hook 116 on the arm 113 when said knuckle is forced into the sphere of action of said lever by the bell-crank 86. It will thus be impossible for the shaft 68 to be 45 further rotated and the box body conveyer arm 67 is held in its outer, or inoperative position if a cover is present or in position over the pin 101, the shaft 68 may be freely rocked by means of the arm 84, the arm 113 being held in position out of the path 50 of the pin 115 against the action of the spring 114 by the pin 101 permitting normal operation of the body feed.

I also provide a device for preventing the feeding of the covers in the absence of a body at the assembling position, this device being illustrated in detail in Fig. 8. As the bodies reach the open section of the channel 28, and approximately at the point indicated by the line 6—6 in Fig. 1, they are 65 engaged by a rear finger 117 on the conveyer

arm 67. It will be noted that the channel 28, in this section of the machine, is formed by the casting 118 at one side and by a plate 119 at the other, said plate being cut away, or slotted, at 121 to permit entrance of the 70 fingers of the conveyer arm 67. The casting opposite this slot is recessed at 122 and a latch 123 is pivotally secured at 124 in this recess. Said latch is normally forced outwardly by a pin 125, which is under the tension of a spring 126. The latch 123 is provided centrally with a beveled surface 127, upon which a body 21 is adapted to act in its forward movement under the influence of the finger 117 on the arm 67. If a body be 80 present at this point, the latch is forced inwardly and the body advanced to the position indicated at 128 in Fig. 8. When the arm 67 is again moved to the left upon the shaft 68, a forward finger 129 on said arm 85 engages the body at the station 128 and the rear finger 117 engages a second cover which has been delivered by the air feed. The forward cover, at this time, is positioned in a recess 131 in the latch 123. Upon the next 90 forward movement of the conveyer arm, the forward body is advanced to the right to the next operating station. In the event that a body 21 is not present to act upon the beveled surface 127 of the latch 123, the 95 finger 117 on the arm 67 is forced outwardly, since the force of the spring 126 acting upon said latch is sufficient to overcome the weight of said arm 67. In this manner, the body conveying arm is moved to inoperative position, which results in lifting the finger 83 by which the covers are advanced with consequent failure to advance a cover to the assembling station. The forward body, meantime, will remain in the recess 131 of the 105 latch. From the foregoing, it will be seen that neither a body nor a cover can be advanced to said assembling station in the absence of a companion part to be assembled therewith.

Assuming that a box body and cover are positioned in adjacent relationship at the assembling station, the next operation is the bending of the hinge lug 23 from the position illustrated in Fig. 17 of the drawing 115 to that illustrated in Fig. 18. The mechanism for performing this operation is perhaps best illustrated in Figs. 6, 7 and 12. A sliding block 132 is carried upon the arm 105 and a forward finger 133 is pivotally 120 connected at 134 to said sliding block 132. The finger 133 is normally held in lifted position by means of a spring-pressed pin 135 projecting from the block 132 and bearing against a lower extension 136 at the rear 125 of the finger 133. Said sliding block 132 is given a reciprocating movement imparted from the slide 91 through mechanism illustrated in detail in Fig. 7. Said mechanism comprises a reciprocating arm 137, which is 130

5 rotatably mounted in a bracket 138 and is provided with a lower projection 139 which is acted upon by the slide 91, and with an upper projection 141 which acts upon the 10 sliding block 132 to move the same in unison with the slide 91, said arm 141 being also adapted to move the slide 132 rearwardly by means of a hook 140 extending beyond said arm at the rear of the slide. Upon movement of the block 132 toward the left, viewing Fig. 12, lower projection 136 on the finger 133 acts upon a pin 142 provided in an upward projection 143 on the retaining plate 99, forcing the forward end of said 15 finger downwardly and against the inner lug 23 on the box body. The forward end of said finger 133 is grooved, as indicated at 144, and thus adapted to accurately engage the lug 23 and bend the same to desired 20 position. Upon the receding movement of the block 132, the finger 133 is lifted by the action of the pin 135. At this point, it may be noted that the arm 105, carrying the sliding block 132 and the retaining plate 99, is 25 provided with a rear extension 145, which is normally pressed upwardly by a spring 146, the upward movement being limited by a set screw 147. In this manner, all lost motion is prevented and the desired limited rocking 30 motion is imparted to the shaft 106.

After the lug 23 is bent downwardly over the corresponding lug 25 on the cover and the hinge thus partially formed, the box is advanced one step toward the right by 35 the action of the succeeding boxes thereon. The next operation is the opening of the box, accomplished by turning the body 21 to the horizontal position shown in Fig. 18, this being done by mechanism illustrated particularly in Fig. 9. An arm 148 is pivoted at 40 149 to a fixed member 151 on the frame and is connected by a curved link 152 with a bell-crank 153 carried on the shaft 87 and operated by a cam 154 on the main drive shaft 82. The arm 148 is provided with a 45 hinged extension 155, which is adapted to engage over the box 21 when in the forward position and to move the same downwardly about its hinge as a pivotal axis to horizontal position. It will be noted that the cover 24, at this point, is held beneath a retaining 50 guide 156 and the body, after being brought to horizontal position and again moved in forward direction, passes under a similar 55 guide 157.

The action of the advancing boxes then 59 brings the partially assembled body and cover to the final clinching station, which is illustrated in Figs. 10 and 11. A sliding toggle mechanism is employed for this purpose and consists of a piston 158 extending through a bearing 150 and having at its front end a bifurcated portion 159 carrying a pivoted member 161 (Fig. 11), which has 65 a lower extension 162 provided with a clos-

ing finger 163, and an upper extension 164 to which is pivotally secured a second closing finger 165. Said finger 165 is also centrally pivoted at 166 on a frame bracket 167 and is forced over center and caused to co-operate with the finger 163 upon forward movement of the piston 158. This results in the final clinching of the lugs 23 and 22 into the relationship shown in Fig. 19, thus completing the hinge. 75

The piston 158 is reciprocated to open and close the clinching jaws by means of a cam 168, which operates an arm 169 connected by links 171 and 172 with said piston 158.

After the assembly of the bodies and 80 covers is completed at this station, the boxes are again moved toward the right in a channel 170 and ejected from the machine.

The main drive shaft 82 is driven by means of tight and loose pulleys 173 and 85 174, the belt being shifted from the one pulley to the other by means of a belt shifter 179. Said shaft 82 has bearings in brackets 175 and 176 depending from the table 27. The shaft 87 is similarly supported from 90 said table 27 by means of brackets 177 and 178.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, 100 the form hereinbefore described being merely a preferred embodiment thereof. 95

I claim:

1. A machine for automatically assembling hinged covers upon metal box bodies, 105 comprising means for advancing the covers and bodies in separated relationship, means for arranging said parts in adjacent relationship, and successively operating devices including hinged connected fingers for bending and clinching together co-operating hinge forming lugs on the covers and bodies. 110

2. A machine for automatically assembling hinged covers upon metal box bodies, 115 comprising means for advancing the covers and bodies in separated relationship and disposed respectively in horizontal and vertical planes, means for arranging said parts in adjacent relationship, and successively operating devices for bending and clinching together co-operating hinge forming lugs on the covers and bodies. 120

3. A machine for automatically assembling hinged covers upon metal box bodies, 125 comprising means for delivering covers and bodies to a given station in alignment and in separated relationship, means for bringing said covers and bodies into juxtaposition with the pintle element of the cover within the flange of the body and the flange of the 130

- cover exterior to the body, and devices for clinching co-operating hinge lugs on the covers and bodies into hinge forming relationship.
5. A machine for automatically assembling hinged covers upon metal box bodies, comprising means for delivering covers and bodies to stationary spaced positions, means for engaging said parts in said positions 10 and advancing them in alignment, means for moving them into juxtaposition with the pintle element of the cover within the flange of the body and the flange of the cover exterior to the body, and devices for bending co-operating lugs in the covers and bodies into hinge forming relationship.
6. A machine for automatically assembling hinged covers upon metal box bodies, comprising means for delivering bodies and 20 covers to given stationary positions in alignment and in separated relationship, means for engaging said bodies and covers and advancing them to an assembling station, means for moving them into juxtaposition, 25 means for clinching together hinge forming parts in the bodies and covers, and means for preventing advance of a body to the assembling station in the absence of a cover in position to be assembled therewith.
7. A machine for automatically assembling hinged covers upon metal box bodies, comprising means for delivering bodies and 30 covers to given stationary positions in alignment and in separated relationship, means for engaging said bodies and covers and advancing them into juxtaposition, means for clinching together hinge forming parts in the bodies and covers, and means for preventing advance of a cover to the assembling station in the absence of a body in 35 position to be assembled therewith.
8. A machine for automatically assembling hinged covers upon metal box bodies, comprising separate channels through 40 which the bodies and covers are fed to an assembling station, means for forming hinge parts of the bodies and covers together into a completed hinge, and safety devices for automatically discharging a portion of the 45 bodies from the body channel in the event of overcrowding therein.
9. A machine for assembling hinged cover metal boxes, comprising means for advancing bodies and covers in angularly disposed 50 and separated relationship to a given sta-
- tion, a conveyer arm engaging the bodies at said station and further advancing the same, means associated with said conveyer arm for further advancing the covers in alignment with the bodies, means preventing operation 70 of said cover advancing means in the absence of a body to be moved by said conveyer arm, means for arranging bodies and covers in juxtaposition when they are advanced together, and means for forming hinges between the juxtaposed flanges of the bodies and covers.
10. A machine for assembling hinged cover metal boxes, comprising means for advancing bodies and covers in angularly disposed and separated relationship to a given 80 station, a conveyer arm engaging the bodies at said station and further advancing the same, means associated with said conveyer arm for further advancing the covers in 85 alignment with the bodies, means for preventing effective operation of said body conveyer arm in the absence of a companion cover for the body being advanced, means for arranging bodies and covers in juxtaposition when they are advanced together, and means for forming hinges between the juxtaposed flanges of the bodies and covers.
11. A machine for assembling hinged cover metal boxes, comprising means for advancing bodies and covers in separated relationship, said advancing means having devices for holding the body and cover at an angle to each other, means for arranging companion bodies and covers with hinge forming lugs in the flanges thereof in overlying 95 relationship, means for bending one of said lugs over the other, means for thereafter fully opening the partially assembled box, and means for finally clinching said body 100 and cover hinge forming lugs into a completed hinge.
12. A machine for assembling hinged cover metal boxes, comprising means for feeding the bodies and covers through angularly arranged channel ways, means engaging the bodies and covers delivered from said ways and advancing them in alignment, means for moving the covers into position adjacent the bodies, and means associated 110 with said last-mentioned cover moving means for bending hinge forming lugs in the bodies over co-operating lugs in the covers to partially form a cover hinge.
13. A machine for assembling hinged 115 cover metal boxes, comprising means for feeding the bodies and covers through angularly arranged channel ways, means engaging the bodies and covers delivered from said ways and advancing them in alignment, means for moving the covers into position adjacent the bodies, means associated with said last-mentioned cover moving means for bending hinge forming lugs in the bodies over co-operating lugs in the cov- 125
14. A machine for assembling hinged cover metal boxes, comprising means for feeding the bodies and covers through angularly arranged channel ways, means engaging the bodies and covers delivered from said ways and advancing them in alignment, means for moving the covers into position adjacent the bodies, means associated with said last-mentioned cover moving means for bending hinge forming lugs in the bodies over co-operating lugs in the cov- 130

ers to partially form a cover hinge, means for opening the partially assembled box, and means for clinching said lugs into a completed hinge.

5. 14. A machine for assembling hinged cover metal boxes, comprising means for advancing flanged bodies and covers to an assembling station, means for arranging the bodies and covers in juxtaposition, and 10 means for interengaging flanged portions on the body and cover to form an integral hinge therein with the pintle element of the cover within the flange of the body and the flange of the cover exterior to the body.
15. 15. A machine for assembling hinged cover metal boxes, comprising means for advancing flanged bodies and covers to an assembling station, means for arranging the bodies and covers in juxtaposition, and 20 means for forming a hinge by interengagement of co-operating flanged portions of the body and cover with the pintle element of

the cover within the flange of the body and the flange of the cover exterior to the body.

16. A machine for assembling hinged cover metal boxes, comprising means for advancing bodies and covers in separated relationship, means for arranging them in adjacent positions, means for causing inter-engagement of co-operating hinge forming lugs on the bodies and covers, and means for clinching said lugs to complete the hinge, said means comprising an automatically operable sliding toggle and clinching fingers operated thereby. 25 30 35

17. A machine for assembling hinged cover metal boxes, comprising cover and body advancing means, and means automatically arranging said parts in assembled and hinged relationship with the pintle element of the cover within the flange of the body and the flange of the cover exterior to the body. 40

JOHN M. HOTHERSALL.
